AMUSEMENT GAME APPARATUS

Lyndon A. Durant, Chicago, Ill., assignor to General Patent Corporation, Chicago, Ill., a corporation of Illinois

Application May 12, 1954, Serial No. 30,422

Term of patent 7 years

(Cl. D34—5)

Fig. 2.

Fig. 1 is a perspective view of an amusement game apparatus showing my new design, the drawing being lined to indicate transparency;

Fig. 2 is a side elevational view thereof, to a reduced scale.

The back of the cabinet is plain, and both sides are substantially the same.

I claim:

The ornamental design for an amusement game apparatus, as shown and described.
